PORTABLE ILLUMINATED SIGN

Harry R. Van Deventer and John J. Shively, New York, N. Y., assignors, by mesne assignments, to Service Devices, Incorporated, New York, N. Y., a corporation of New York

Application June 20, 1935, Serial No. 27,488

5 Claims. (Cl. 40—132)

This invention relates to illuminated signs, and more particularly to such signs of the portable type which can be readily carried from place to place and used for window displays and the like.

5 An object of the invention is to provide a portable sign of the type described which is entirely self-contained including a suitable source of energy for operating the sign.

Another object is to provide a sign of this 10 type in which batteries are used as a source of current supply and wherein the said batteries can be removed and replaced without the necessity of disconnecting wires therefrom.

A further object is to provide a sign of this 15 type in which a gaseous tube, such as a neon tube for example, is used and operated by alternating or interrupted current obtained from a source and means forming part of the complete sign unit and movable therewith.

20 Other objects will be apparent from the following specification, in which a preferred type of sign embodying the invention is described by way of illustration.

The invention consists substantially in the construction, combination, location and relative arrangement of parts, all as will be more fully hereinafter set forth and as shown by the accompanying drawings and finally pointed out in the appended claims.

25 In the accompanying drawings:

30 Figure 1 is a rear view of a sign embodying the invention with the back removed;

Figure 2 is a view, partly in cross section, on the line 2—2, Figure 1; and

35 Figure 3 is a schematic diagram of the wiring of the sign, Figures 1 and 2.

In the copending application, Serial No. 19,039, filed April 30, 1935, is described a sign of the general character of that herein disclosed except the 40 aforesaid application discloses a power operated sign, designed for use with 110 volt alternating current and adapted to be connected to an ordinary lighting circuit via the cord and plug shown. The present invention distinguishes from the 45 power operated sign aforesaid in that it does not require connection to a power circuit, but is entirely self-contained, the source of energy for operating the sign being enclosed within the casing thereof. This eliminates the plug and cord 50 and all external connections and enables the sign to be carried about while illuminated, and has many other advantages.

It will be understood, however, that this improved sign employs a gaseous tube as a source 55 of light and in external appearance is similar

to the sign described in the aforesaid copending application.

The numeral 10 denotes a front casing or frame 5 preferably of insulating material such as bakelite. Within this frame is supported the transparent panel or glass 11 and in the rear thereof is positioned the grid 12 formed of a piece of neon tubing or the like, forming a gaseous tube adapted to glow when the terminals thereof are connected to a suitable source of current.

Panel 11 can be omitted and the grid 12 and reflector 13 to be presently described, mounted within the casing 10. When this is done any suitable medium, such as a stencil or perforated plate, can be used in front of the grid to form the 15 sign proper. The panel 11 or any other medium placed in front of the grid is hereinafter termed "sign indicia".

Immediately behind said grid and partially supported thereby is located the reflector 13, held 20 in place and pressed outwardly by the resilient strips 14 of sponge rubber or the like, which are supported on the mounting plate 15 secured to and partially closing the rear of the frame 10, except for the apertures 15a, 15b, 15c, to provide 25 for ventilation to the interior of the casing.

All of the foregoing assembly is practically the 30 same as that shown in the copending application heretofore mentioned and is referred to herein merely by way of illustrating the invention to be presently described. The arrangement of casing, grid, reflector and mounting plate may be varied within wide limits without departing from the appended claims wherein these elements are claimed in combination with the new and useful elements 35 hereinafter disclosed.

The mounting plate 15 has secured thereto in any suitable manner, a transformer having a primary winding 16 and a secondary winding 17 the latter being connected directly to the terminals of the grid 12, as shown in Figure 3.

40 The primary 16 is connected to an interrupter generally indicated by the numeral 18 applied to the base thereof to indicate that the interrupter may, if desired, be made on a base and removable as a unit from the mounting plate 15. This interrupter may be of any desired type, either a vibrating device as shown, a thermionic device, a commutator whereby a true reversal of polarity is obtained or any other device, several of which are known, that will modify the direct current output from a suitable source of energy such as the batteries 28 so that it will, via the transformer windings 16, 17, operate the gaseous tube or grid 12 and illuminate the same.

45

50

55

The interrupter unit shown here merely as illustrative of such a device, comprises a base 18 upon which is insulatedly supported in any suitable manner the reed 19 having an armature 20 adapted to be attracted by the core 21 of an electromagnet, the winding 22 of which is in series with the contacts 23, one of which moves with reed 19.

Another set of contacts 24 controls the circuit 10 through the primary 16 of the transformer, as shown in Figure 3.

A switch 25 is mounted on an extension 26 carried on the plate 15 and projects through an opening in the back 27 which can therefore be removed from the front 10 without disturbing any of the wiring or apparatus as nothing is secured thereto. This switch is in series with the battery comprised of the cells 28, as many as necessary being employed.

20 The first cell 28a of the battery is provided with a contact member 29 insulatedly mounted on plate 15 and adapted to automatically contact with and engage one of the terminals of the cell. A support 30 is also provided and insulated from plate 15.

Each succeeding cell 28 is provided with a similar independently insulated contact member 29a and an independent support 30 insulatedly mounted on the plate 15.

30 The contact members 29a and supports 30 are connected as shown in Figure 1 and all the cells 28a, 28 are therefore in series between the first contact member 29 and the last support 30a.

The first contact member 29 is connected to the primary winding 16 of the transformer and to the electromagnet winding 22 of the interrupter. The last support 30a is connected to the switch 25, all as shown in Figures 1 and 3.

40 The members 29, 29a and 30, 30a, have sufficient tension to permit the battery cells to be securely gripped in operative position. Should it be necessary to replace a cell, it is merely pulled out of its support and another forced into position. This obviates all wire connections and the use of tools and is a change that can be successfully performed by the most unskilled.

45 In operation, the switch 25 being closed, current flows from terminal 30a of the battery 28 through contacts 23 to winding 22 of the vibrator 50 and to terminal 29 of the battery 28a via conductor 31.

55 As the reed 19 vibrates, due to the operation of the core 21 and contacts 23, the circuit (from 30a via switch 25, contacts 24, conductor 32, primary 16 and terminal 29 via conductor 33) is interrupted. This actuates the transformer, the secondary winding 17 of which being directly connected to the grid 12, causes the latter to glow.

Condensers 34, 35 are connected across the 60 contacts of the interrupter to prevent excessive sparking and to smooth out and augment by their charge, the current delivered to the transformer.

A handle 36 may be provided so that the sign 65 may be carried from place to place (while in operation if desired) and as no outside source of current is necessary the sign may be operated anywhere desired.

70 By proper design of the associated parts, ordinary dry cells which can be obtained practically everywhere, can be used as a source of current and are easily and cheaply replaced when exhausted.

75 It will be seen from the foregoing that the invention provides a unitary sign structure comprising in a single portable casing, a glow tube

adapted to form what is in effect a sheet of neon glow illuminating the area of the glass 11, and all the necessary means for exciting said tube including a source of direct current and means (the interrupter) for utilizing this through the 5 transformer to excite the glow tube.

It will also be noted that the output of the transformer, that is the voltage of the secondary 17, may be 5,000 or more. This would be painful if not dangerous to anyone coming in contact therewith. But by making the casing 10 and 10 27 of bakelite and completely enclosing all metal parts (the projecting parts of the switch 25 may be of insulating material) complete safety for the user is assured, for without removing the back 15 27 the user cannot get in contact with any live parts of the device or any metal parts whatever.

Although the invention has been disclosed in connection with the specific details of preferred embodiments thereof, it must be understood that 20 such details are not intended to be limitative of the invention except in so far as set forth in the accompanying claims.

What is claimed is:

1. A portable sign comprising in combination, 25 a source of electric current, an interrupter in circuit therewith, a transformer having a primary winding in circuit with said source and said interrupter, a secondary winding on said transformer, a gaseous tube grid connected to said secondary winding, a casing within which all of the aforesaid elements are mounted, a transparent panel in the front of said casing, means to position sign indicia in front of said panel, said grid engaging the inner face of said panel whereby said grid is adapted to illuminate 30 said indicia when in operation, and resilient means urging said grid against said panel.

2. A portable sign comprising a casing forming a frame having a transparent panel closing the front thereof, said panel supporting sign indicia, a gaseous tube positioned behind said indicia, a reflector behind said tube, resilient mounting means to press said reflector against said tube and said tube outwardly against said 40 panel, a mounting plate supporting said resilient mounting means and adapted to partially close the back of said frame, a plurality of battery cells mounted upon said plate, a transformer mounted on said plate, and an interrupter mounted on said plate, said interrupter being in 45 series with said battery cells and the primary of said transformer, the secondary of said transformer being connected to the terminals of said gaseous tube.

3. A portable sign comprising in combination, 50 a source of electric current, a transformer having a primary winding in circuit with said source, a mounting plate upon which said source of current is insulatedly supported together with said 55 transformer, an interrupter in circuit with said source of electric current and said primary winding said interrupter having a base forming a unit therewith adapted to be mounted on said mounting plate, a secondary winding on said transformer, a gaseous tube connected to said secondary winding, and a casing of insulating material within which all of the aforesaid elements are mounted to permit the illumination of said tube to act as a sign.

4. A portable sign comprising in combination, 60 a source of electric current, an interrupter in circuit therewith, a transformer having a primary winding in circuit with said source and said interrupter, a secondary winding on said 65 70 75 transformer.

transformer, a gaseous tube connected to said secondary winding, a casing of insulating material within which all of the aforementioned elements are mounted, a metallic reflector positioned back of said gaseous tube and in contact therewith, a resilient insulating member tending to press said reflector in contact with said tube, and means comprising a mounting plate secured to said casing and holding said resilient insulating member in position, said transformer and interrupter being mounted on said plate.

5. A portable sign comprising in combination a casing having a front opening therein, a transparent panel closing said front opening, a gaseous tube positioned behind said panel and partially supported thereby, a reflector behind said tube, resilient means in contact with said re-

flector, a mounting plate bearing against said resilient means, said plate being secured to said casing and enclosing together therewith said tube and reflector, a source of electric current mounted within said casing, an interrupter in circuit with said source, a transformer having a primary winding in circuit with said source and said interrupter, said source of current and transformer being mounted on said plate and enclosed by said casing, a secondary winding on 10 said transformer connected to said gaseous tube, and switch means having a portion extending outside said casing adapted to control said source of electric current and connected in circuit with said source of electric current. 15
